TEXTILE FABRIC

Clement R. Howell, Winnsboro, S. C., and James F. Fulton, Birmingham, Mich., assignors to United States Rubber Company, New York, N. Y., a corporation of New Jersey

Application September 17, 1956, Serial No. 42,950

Term of patent 14 years

(Cl. D92—1)

Fig. 1 is a plan view of a textile fabric showing our new design;

Fig. 2 is a sectional view of the fabric of Fig. 1 along the line 2—2;

Fig. 3 is a sectional view of the fabric of Fig. 1 along the line 3—3, and

Fig. 4 is a sectional view of the fabric of Fig. 1 along the line 4—4.

The design is embodied in a textile fabric having a surface of raised puffs appearing as light areas in Fig. 1. In the embodiment shown, the puffs are held raised by

threads interlaced in the fabric that are represented by the straight lines in Figs. 2, 3 and 4.

We claim:

The ornamental design for a textile fabric, as shown and described.
